UNITED STATES PATENT OFFICE.

JOHN M. MARIS, OF CHICAGO, ILLINOIS.

SELF-DUMPING CAR FOR COKE.

SPECIFICATION forming part of Letters Patent No. 630,385, dated August 8, 1899.

Application filed March 17, 1899. Serial No. 709,499. (No model.)

To all whom it may concern:

Be it known that I, JOHN M. MARIS, a citizen of the United States, residing in Chicago, in the county of Cook and State of Illinois, 5 have invented a new and useful Improvement in Self-Dumping Cars for Coke and other Materials, of which the following is a specification.

My invention relates to improvements in 10 the construction of cars, and more particularly to improvements in automatic or self-dumping cars for hauling coke and other materials.

Heretofore in the construction of cars the 15 longitudinal sills of the car-body spanning or connecting the front and rear bolsters have been stiffened and strengthened to enable them to support the car-body itself and its load without deflection between the bolsters 20 by means of strong truss-rods applied thereto, the truss-rods being supported on suitable struts projecting downwardly from the sill, and as in large long cars designed for carrying heavy loads it is necessary that the 25 trusses shall extend or project a considerable distance below the sills in order to be effective and adequately strengthen and stiffen the sills the car-body itself is necessarily supported a considerable distance above the 30 railway-track by building the trucks high, thus materially diminishing the height and capacity of the car-body *w x*, as the total height of the car is limited, and also increasing the liability of the car to leave the track 35 by rendering it top-heavy. The necessity of using strong trusses to stiffen the longitudinal sills of the car-body also of course adds materially to the cost of the car.

It is the object of my invention to provide 40 a simple, cheap, efficient, and durable construction of car for hauling coke or other materials by which the necessity for employing truss-rods applied to and projecting below the longitudinal sills of the car-body may be 45 entirely dispensed with and which will at the same time be much stronger and stiffer than the ordinary construction of trussed-car bodies heretofore in use, thus not only saving the expense of the separate trusses, but also enabling the trucks to be built as low as desired and the car-bodies supported at as little 50 height above the ground or railway-track as

may be required or thought desirable by the user or builder of the car and enabling the car-body box to be made materially lighter 55 and of greater capacity.

My invention consists in the means I employ to practically accomplish this useful and important object or result—that is to say, it consists in the combination in a car of the 60 longitudinal sills thereof with an inclined steel-plate bottom therefor connected with the sills, so that the inclined bottom serves not only its ordinary function of automatically dumping or discharging the coke or material in the car, but the additional function 65 by reason of its vertical component and its connection with the sills of an effective truss or device for strengthening and stiffening the sills to enable them to support the load. The 70 longitudinal sills and the connected inclined bottom of the car-body thus together form a continuous and unitary structure extending from end to end of the car and triangular in cross-section and which as a whole possesses 75 very great strength and stiffness in resisting the weight of the load or vertical deflection, as the vertical height of the unitary structure from the bottom edges of the longitudinal sills to the peak or ridge of the inclined 80 bottom is very considerable and as the whole body of steel or metal in the inclined bottom is utilized and made effective in giving strength and stiffness to the longitudinal sills or to the structure as a whole. To adequately connect the steel plates of the inclined bottom with the longitudinal sills of the car and to further strengthen and stiffen the structure as a whole, the inclined bottom plates are provided with vertical flanges at 85 90 their outer edges, overlapping and riveted to the longitudinal side sills of the car-body. The inclined bottom for each side is preferably not formed in one integral plate extending from end to end of the car-body, as that 95 would be an inconvenient length of plate to obtain and handle; but the inclined bottom for each side thereof is preferably or most conveniently formed of a series of steel plates connected at their lower or outer edges to the 100 longitudinal side sills of the car-body and connected at the upper edges to a longitudinal ridge-bar at the ridge or peak of the inclined bottom and connected together at their

meeting side edges by metal beams, T-irons, or frame-pieces, so as to act as a continuous truss or plate extending from end to end of the car-body, the connecting metal beams, 5 T-irons, or frame-pieces serving also as struts to prevent buckling of the truss-acting inclined bottom plates.

My invention also consists in the novel construction of parts and devices and in the 10 novel combinations of parts and devices herein shown and described, and specified in the claims.

In the accompanying drawings, forming a part of this specification, Figure 1 is a vertical cross-section of a car-body embodying my invention, the car-body shown being specially designed as one for hauling coke. Fig. 2 is a partial central longitudinal section taken on line 2 2 of Fig. 1. Fig. 3 is a partial plan view with the bottom plates removed. Fig. 4 is a side elevation of the car-body sills and inclined bottom, the inclined bottom plates being in part removed.

In the drawings similar letters of reference 25 indicate like parts throughout all the figures.

In the drawings A A' represent the longitudinal sills of the car-body, the longitudinal side sills A A being preferably steel channel-beams and the central or draw sills A' A' 30 being preferably steel I-beams. The longitudinal sills A A' A' are suitably spaced apart and connected together by transverse connecting-bars a and by the lower members b of the triangular frames B, upon the upper members b' of which the inclined bottom D is supported. The upper or inclined sides or members b' b' of the triangular frames B are preferably formed integral with each other or out of a single T-iron beam by bending 35 the same at the required angle at the middle or ridge of the inclined bottom. The members b' b' of the triangular frames B are connected together at their lower angles by angle-plates b² b² and are suitably braced and 40 strengthened at the ridge of the inclined bottom by angle-plates b³, riveted to the vertical flange of the bent T-iron. The triangular frames B are further stiffened by braces b⁴, connecting the horizontal member b and the 45 inclined members b' b' thereof, as will be readily understood from Fig. 1. These braces b⁴ cause the triangular frames to act more effectively as struts to prevent buckling or deflection of the truss-acting inclined steel-plate bottom D of the car-body under either 50 tension or compression strains.

C is the ridge-bar, extending longitudinally of the car from end to end at the peak or ridge of the inclined bottom and to which 55 the steel plates composing the inclined bottom are secured at their upper meeting edges by rivets d, extending through the upright flanges d' d', formed at the meeting edges of the inclined bottom plates. The inclined bottom plates D are further each provided with an upright flange or bend d² at their outer or bottom edges, fitting flat against and

securely connected with the longitudinal side sills A A of the car-body by rivets d³, thus securely uniting the inclined bottom to the 70 longitudinal sill structure of the car-body, so that the inclined bottom will act and operate in unity with the longitudinal sills in giving strength and stiffness to the car-body or structure as a whole. Where the inclined bottom plates D for each side of the double inclined bottom are made in separate plates or pieces, as I prefer to construct them and as illustrated in the drawings, the individual plates or pieces D thereof are preferably connected together, so as to serve as a continuous truss-acting plate from end to end of the car-body, not by overlapping the edges of individual plates D and riveting them directly together, but by abutting the meeting edges 80 of the individual plates together and riveting each of the two meeting plates to the connecting and supporting triangular frame B. This gives a smooth surface to the inclined bottom, and the strut-acting triangular supporting-frames B are thus also located at the joint connecting the individual plates D of the inclined bottom, where they are most needed to prevent buckling of the truss-acting inclined bottom plates in cases where said 90 bottom plates are made in separate pieces.

F F are the vertical posts for the upper box portion of the car-body frame, the same being preferably composed each of two angle-irons secured together, with a space between, by 100 bolts or rivets f² and spacing-washers f³; F', the upper longitudinal sills of the car-body frame; F², the hinged roof-doors, and F³ the carlines or transverse beams of the roof-frame. The posts F are furnished with bent or inclined portions f to contract the width of the lower portion of the car-body box to the distance between the longitudinal sills A A. These posts are securely riveted to the longitudinal side sills A A and also to the longitudinal car-box sills F' F', which are preferably channel-beams. The posts are connected to the roof-plates F⁴ F⁴, which are preferably of wood, by bolts f', as indicated in the drawings.

G G are the inclined dumping doors or gates of the car, the same fitting between the webs f⁵ of the double angle-iron posts F F and shutting against the flanges f⁶ thereof. These doors or gates G are hinged or pivotally connected to the longitudinal car-box sills F' F' 120 at their upper edges by pivots or hinges g and are held closed at their lower edges by the connecting rod and chain g' g², the chain being connected to and winding around the windlass G', secured to a winding-shaft G², suitably mounted or journaled under the inclined bottom at the apex or ridge thereof in the supporting-frames B B. The winding-shaft G² is provided with a pawl and ratchet and 125 operating-lever at its end. At each end the car-body is provided with an end plate H, preferably of steel, the same being securely riveted to the posts F at the end of the car- 130

body and also to the frame B at the end of the car-body.

K is the roof of the car, which may be of any suitable construction, and M are transverse T-iron beams connecting the longitudinal channel-sills F' F', and N N are the slats of the car-body box, the same being secured to the posts by bolts or suitable means.

The inclined bottom plate is furnished with 10 slots d^4 , through which the connecting rod or link g', leading to the hinged doors or gates, extends.

The ridge-bar C is not necessarily made in one integral piece extending from end to end 15 of the car, but may be made in two or more pieces, if desired, for convenience in handling, care being taken that the joint between the two separate pieces of the ridge-bar shall not come at the same point as the joint between 20 adjacent bottom plates D D.

P is the body-bolster of the car, the same being secured to the car-body on the under side thereof and extending between the side sills A and longitudinal sills A', said car-body 25 bolster having an upper portion P', extending from side sills A A over the draw-sills A' A'. The two portions of the body-bolsters P and P' are directly over each other. It will be understood that the cross-section, Fig. 1, shows 30 only one half the length of the body-bolster, the other half of the body-bolster being removed in order to better show the other parts.

I claim—

1. In an automatic or self-dumping car-body, the combination with the body-bolsters and longitudinal sills, of an inclined truss-acting continuous car-body bottom having two oppositely-inclined sides connected rigidly together at their upper meeting edges 40 and rigidly connected at their lower edges with the sills from end to end to strengthen and stiffen the same, substantially as specified.

2. In a car-body, the combination with the 45 body-bolsters and longitudinal sills thereof, of an inclined, continuous truss-acting bottom for the car-body connected with the sills and supported and connected to a series of strut-acting frames of triangular shape secured to the sills, substantially as specified.

3. In a car-body, the combination with the 50 body-bolsters and longitudinal sills, of a series of triangular frames rigidly secured thereto, and a truss-acting inclined bottom for the car-body, composed of a series of metal plates

secured at their lower edges to the longitudinal side sills of the car-body and secured together at their upper meeting edges at the ridge or peak of the inclined bottom, and secured together at their meeting side edges by 60 said triangular frames to which they are rigidly connected, substantially as specified.

4. In a car-body, the combination with the longitudinal sills, of a series of triangular frames rigidly secured thereto, and a truss- 65 acting inclined bottom for the car-body, composed of a series of metal plates secured at their lower edges to the longitudinal side sills of the car-body and secured together at their upper meeting edges at the ridge or peak of 70 the inclined bottom, and secured together at their meeting side edges by said triangular frames to which they are rigidly connected, and a ridge-bar at the upper meeting edges of said inclined bottom plates, substantially 75 as specified.

5. In a car-body, the combination with the body-bolsters and longitudinal sills of a double-inclined truss-acting continuous bottom connected to said sills and extending as a 80 truss from end to end of the car-body, a winding shaft and drums mounted under the ridge or peak of said inclined bottom, and dumping doors or gates hinged at their upper edges to the car-body, and connections from the winding-drums to said doors or gates, substantially 85 as specified.

6. In an automatic or self-dumping car-body, the combination with the longitudinal sills and inclined bottom of the car-body, of 90 a series of posts F F, a series of hinged doors G G fitting between the webs of said posts and shutting against the flanges thereof, a winding shaft and drums, and connections leading from the winding-shaft to said hinged 95 doors or gates, substantially as specified.

7. In a car-body, the combination with the longitudinal sills, of a series of triangular frames rigidly secured thereto, a truss-acting 100 inclined steel-plate bottom for the car-body having flanges at their lower edges riveted to the longitudinal side sills of the car-body and provided with flanges at their upper meeting edges, and a ridge-bar fitting between and riveted to said last-mentioned flanges of the 105 bottom plates, substantially as specified.

JOHN M. MARIS.
